Exhibit 1: Four photos of a prior art case of Rehrig Pacific Company, Model No. PLBC-8-2L-PET-QD (1984).

Exhibit 2: Two photos of a prior art case of Rehrig Pacific Company for 3 liter PET bottles (1990).

Exhibit 3: Two photos of a prior art case of D.W. Plastics (Date unknown).

Exhibit 4: Two photos of a prior art case of International Container Systems, Inc. for 3 liter PET bottles (Date unknown).

Primary Examiner—Dominic Simone

(74) *Attorney, Agent, or Firm*—Brooks & Kushman P.C.

CLAIM

The ornamental design for a stackable low depth tray, as shown and described.

DESCRIPTION

FIG. 1 is a perspective view of the stackable low depth tray according to the present invention;

FIG. 2 is a top plan view of the tray of FIG. 1;

FIG. 3 is a bottom plan view of the tray of FIG. 1;

FIG. 4 is a front side elevational view of the tray of FIG. 1,

the rear side elevational view being a mirror image thereof;

and,

FIG. 5 is a right side elevational view of the tray of FIG. 1,

the left side elevational view being a mirror image thereof.

1 Claim, 5 Drawing Sheets
